(57) **CLAIM**

The ornamental design for an instrument effects box, as shown and described.

DESCRIPTION

FIG. 1 is a perspective view of an instrument effects box showing my new design;

FIG. 2 is a top plan view thereof;

FIG. 3 is a right side elevational view thereof, the left side elevational view being a mirror image;

FIG. 4 is a rear elevational view thereof; and,

FIG. 5 is a front elevational view thereof.

The bottom plan view is unornamental and forms no part of the claimed design.
